UNITED STATES PATENT OFFICE.

OTTO PEARSON, OF MOUNT JEWETT, PENNSYLVANIA.

MEANS FOR CONNECTING THE FRONT ENDS OF SLED-RUNNERS.

1,127,673.

Specification of Letters Patent.

Patented Feb. 9, 1915.

Application filed May 18, 1914. Serial No. 839,388.

To all whom it may concern:

Be it known that I, OTTO PEARSON, a subject of the King of Sweden, residing at Mount Jewett, in the county of McKean and State of Pennsylvania, have invented certain new and useful Improvements in Means for Connecting the Front Ends of Sled-Runners; and I do declare the following to be a full, clear, and exact description 10 of the invention, such as will enable others skilled in the art to which it appertains to make and use the same.

This invention relates to improvements in sleds and more particularly to the means 15 for connecting the front ends of the runners and the steering bar to the runner connecting bar.

The object of the invention is to provide simple and efficient means of this character 20 which will reliably connect the front ends of sled runners without weakening them thereby avoiding all danger of their breakage when under severe strain.

With this and other objects in view the 25 invention consists of certain novel features of construction, and the combination and arrangement of parts as will be hereinafter described and claimed.

In the accompanying drawings: Figure 1 30 represents a side elevation of a sled illustrating the application of one form of this invention: Fig. 2 is a front elevation thereof: Fig. 3 is a detail horizontal section taken on line 3—3 of Fig. 1: Fig. 4 is a longitudinal section of a portion of a sled taken 35

on line 4—4 of Fig. 2: Fig. 5 is a similar view taken on line 5—5 of Fig. 2: Fig. 6 is a detail side elevation of a portion of the front end of a sled illustrating another form 40 of the invention: Fig. 7 is a detail perspective view thereof: Fig. 8 is a similar view of the runner connecting bar: Fig. 9 is a detail side elevation of the front end of one of the runners used in this form of the invention.

45 In the embodiment illustrated side bars 1 are shown connected at their front ends by the usual cross bar 2. A handle bar 3 is mounted on a steering bar 4 which is pivotally connected at one end with the seat 5 of the sled and has its free front end offset

downwardly and extended laterally and then bent upwardly to form a hook-like engaging member for connecting said steering bar with the runner connecting cross bar 7. This cross bar 7 is provided with three 55 longitudinally extending slots 8, 9 and 10 arranged at the opposite ends and at the center of said bar, the end slots being designed to receive hook members 11 formed on the front ends of the runners 12 and the 60 central slot to receive the hook 6 of the steering bar 4.

The runners 12 which are preferably made of metal in the form of angle irons have their front free ends bent downwardly 65 to form the hooks 11 which when engaged with the slots 8 and 10 of the cross bar 7 securely connect said runners to said cross bar without any rivets being necessary and thereby forms a reliable and strong connection 70 at these points.

In the form shown in Figs. 6 to 9 which is specifically claimed in my copending application Serial No. 869,933, filed Nov. 2, 1914, the runners 12' are constructed in the 75 form of angle bars T-shaped in cross section, the webs 13 thereof at the front ends of the runners being slotted longitudinally as shown at 14 to receive hooks 15 formed on the ends of the metal cross bar 16. This 80 cross bar 16 is provided intermediately of its ends preferably at a point midway thereof with a slot 17 with which the hooked end of the steering bar is designed to be engaged.

85 My invention adapts the connecting bar to be readily detached from the runners at will without removing any rivets or bolts which is regarded by me as an important feature of my invention adapting the sled 90 to be readily assembled and disassembled.

I claim as my invention:

1. In a sled the combination of runners, a cross bar connecting said runners and having a longitudinally extending slot midway 95 the ends thereof, and a steering bar having its free end bent to form a hook adapted for engagement with the slot in said cross bar.

2. A sled including runners and a cross bar connecting them, said cross bar being 100

provided with a plurality of longitudinally extending slots and hooks on said runners for detachably engaging the slots in said cross bar whereby said cross bar and runners are held in interlocking engagement.

In testimony whereof I have hereunto set

my hand in presence of two subscribing witnesses.

OTTO PEARSON.
